UNITED STATES PATENT OFFICE

OSCAR A. JOURET, OF MOOSUP, CONNECTICUT, ASSIGNOR TO THE LESTER & WASLEY COMPANY, INC., OF NORWICH, CONNECTICUT, A CORPORATION OF CONNECTICUT

DECKLING AND SCORING MACHINE

Application filed October 22, 1928. Serial No. 314,159.

This invention relates to improvements in machines for working on paper, card-board and the like, and is directed particularly to improvements in machines for simultaneously deckling and scoring, creasing, or slitting paper and similar materials.

It has become common practice to deckle or bevel the edges of paper to obtain artistic effects by means of rotating cutting tools which 10 act on said edges. According to this invention I provide means for co-operating with the deckling or beveling mechanism referred to which is adapted to act on the material simultaneously with said mechanism for scoring, creasing, or slitting the same.

To this end I am enabled to produce a sheet having deckled edges which is scored or creased for folding or a plurality of bevelled edged sheets which are severed by the slitting action.

The invention is capable of broad application but for purposes of disclosure will be described in connection with the accompanying drawings in which:

25 Fig. 1 is a plan view of an apparatus having the features of the invention embodied therein.

Fig. 2 is a side elevation view showing rolls which may score, crease or slit a web simultaneously with the deckling or beveling thereof, and

Fig. 3 is a front elevational view of the same.

Referring to the drawings the invention 35 will now be described in detail. 1 and 2 represent suitable stands in which are rotatably supported upper and lower shafts 3 and 4. These shafts have adjustable therealong coacting pressure rolls or wheels R which are adapted to feed a sheet of paper or the like forwardly from a feed table F to a delivery table D, the said shafts being suitably geared together by gears G for uniform rotation. Either one of said shafts may be 40 utilized as the driving shaft for the other and may carry a driving pulley 6 or one of them may be geared to a motor. A suitable guide 8 is adjustable on the table F and serves to guide a sheet in a feeding movement, so as to present its edge to a rotating

deckling tool T which is rotated by a motor M suitably connected thereto by gears.

The stands 1 and 2 are secured to the ends of a transverse bed member B and the upper shaft 3 is preferably adjustable up and down in the stands so that said shaft may be moved towards and away from the lower shaft 4. The structure just described is similar to that shown and described in the U. S. patent to Joseph N. Fountain No. 1,607,193 dated November 26, 1926, and need not be gone into in further detail except to say that if desired deckling tools and associated mechanisms may be located at opposite sides of the table F as in the patent referred to so as to 55 simultaneously deckle or bevel opposite sides of a sheet or web.

The upper shaft which is rotatable as aforesaid I make use of according to my invention for supporting a slitting, creasing, or scoring member S which has a peripheral working edge for coacting with a roll S' rotatable therebelow in a bracket 16. The rolls S and S' may take any form desired and may be arranged to either score, crease or slit a web 60 of paper passing therebetween.

According however to one form of the invention I have shown the roll S' as having a scoring or creasing edge and the roll S as having a groove to co-operate therewith so as to 65 increase or score a sheet of paper.

According to one novel feature of the invention the upper roll S is made so as to be separable and also adjustable along the shaft so that it may be removed or affixed thereto 70 accordingly as it is desired to score, crease, and slit a sheet intermediate its side edges.

In the form shown the upper roll S comprises a pair of upper semi-circular side plates 18 and a lower pair of similar plates 20. Each pair of plates has secured therebetween as by dowels 19 or the like inner half-disc-like tool members 24 the outer peripheral edges of which are formed to have a 75 circumferential periphery suitable for scoring, creasing, or slitting a web.

The upper plates 18 are affixed to the lower plates 20 by clamping screws 28 as shown which function to draw the parts together so 80 that they securely embrace the shaft which 100

may pass through a central axial opening as shown.

Opposite ends of each of the members 24 are arranged so that one end such as 24' will 5 extend beyond the plates 18 and 20 to form a tongue. The shorter end of the members serves in conjunction with the plates to which they are secured to provide a slot for receiving the said tongues. As will be seen the 10 extension or tongues 24' of the lower member extends upwardly between the upper plates 18 while the extension 24' of the upper member extends downwardly between the lower plates 20. With this arrangement the 15 pairs of plates may be assembled in one way only so as to insure that the outer working edges of the tool members 24 are in accurate register.

The lower roll S' in the form shown has a 20 substantially sharp scoring periphery and is journaled for rotation in the bracket 16 which is movable along the bed and secured thereto in various positions of adjustment by means of a clamp 32 and screw 34. The roll 25 S' may be formed so as to co-operate with the upper roll S for a slitting, creasing or scoring action and the bracket may be clamped to the bed in any desired manner but obviously will be arranged and adapted to position the 30 roll S' so that it will co-operate effectively with the upper roll S. An adjusting screw A in the bracket 16 is adapted to abut the upper side of the bed for raising or lowering it so that the rolls may be brought to bear against 35 one another with varying degrees of pressure to thereby obtain various scoring or creasing effects. In operation the roll S is secured in the desired location to the shaft 3 and the bracket 16 is fixed to the bed therebelow so that as a sheet of paper is fed forwardly by 40 the rolls it is acted upon by the rolls S and S' for a scoring, creasing or slitting action according to the type of rolls employed.

The rolls may be located at various distances from the deckling or bevelling mechanism and as many sets of rolls may be employed as may be desired to the end that simultaneously with the deckling action the paper or material is also scored, creased or severed by slitting.

By means of the mechanism described it is not only possible to simultaneously score, crease or slit the deckle material so as to avoid separate working operations but especially where a scoring operation is performed the rolls function in co-operation with the rolls R to feed the material forwardly and to maintain it in alignment with the guide 8.

As before stated the form of the rolls S and S' may be varied within wide limits accordingly as it is desired to score, crease or slit the material simultaneously with the deckling operation and by means of the novel construction the rolls may be readily and easily affixed to the rotatable shaft in any

desired location. The bracket 16 of course may be moved so that the roll S' may co-operate with the upper roll and by means of the adjustment provided the roll S' may be moved towards and away from the upper roll 70 so as to obtain any desired degree of pressure.

The apparatus may be changed or modified within wide limits to adapt the novel features of the invention to various conditions and to 75 accomplish various results without departing from the spirit and scope of the invention and therefore I prefer to be limited by the appended claims rather than by the foregoing description of the preferred form of the invention.

What I claim and desire to secure by Letters Patent of the United States is:

1. An apparatus of the class described comprising in combination, pairs of semi-circular plates, each having shaft embracing apertures, means for clamping the pairs of plates together about a shaft, sheet working semi-circular members secured between the plates of each pair having their outer end portions arranged so that one end of the member of one pair fits between the plates of the other pair. 85

2. An apparatus of the class described comprising in combination, pairs of semi-circular plates having shaft embracing apertures, hubs extending outwardly from said plates and means for securing the hubs together to clamp the plates to a shaft, semi-disc-like members secured between the members of each pair, each of said members having relatively short and long ends at opposite sides thereof whereby there is provided interfitting tongues and sockets for each pair of plates. 95

3. An apparatus of the class described comprising in combination, pairs of semi-circular plates having shaft embracing apertures and means for clamping the pairs to a shaft, semi-disc-like sheet working members fixed between the plates of each pair, opposite sides of the members disposed respectively below and above the sides of the plates to provide a socket and a tongue at opposite sides of each pair of plates whereby the 115 tongues and sockets may interfit when the pairs of plates are clamped to a shaft. 110

4. An apparatus of the class described comprising in combination, a bed, a shaft rotatable thereabove, a bracket adjustable on said bed, a roll on said shaft and a roll co-acting therewith journaled on said bracket and means associated with said bed and bracket for moving said bracket and roll carried thereby towards and away from the roll 120 on said shaft. 125

5. An apparatus of the class described comprising in combination, a bed, a pair of shafts rotatable thereabove, co-operating feed rolls on said shafts for feeding a sheet, a bracket 130

adjustable on said bed, coacting rolls for acting on a sheet fed forwardly by said feed rolls, one of which is mounted on one of said shafts and the other of which is rotatable on said bracket and means associated with said bed and bracket for moving said bracket and roll carried thereby towards and away from the shaft carrying said roll.

6. An apparatus of the class described comprising in combination, a bed, a pair of shafts rotatably supported thereby, co-operating feed rolls on said shafts for feeding a sheet, a bracket adjustable on said bed having a bearing portion between said shafts, coacting rolls for acting on a sheet fed forwardly by said feed rolls one of which is mounted on one of said shafts and the other of which is rotatable on the bearing portion of said bracket and means associated with said bed and bracket whereby said bearing may be moved to move the roll therein towards and away from the other.
